Primary Examiner — Paula Allen Greene(74) *Attorney, Agent, or Firm* — Daniel Rose; Foley & Lardner LLP(57) **CLAIM**

The ornamental design for headphones, as shown and described.

DESCRIPTION

FIG. 1 is a front perspective view of an embodiment of headphones;

FIG. 2 is a front view of an embodiment of the headphones of FIG. 1;

FIG. 3 is a rear view of an embodiment of the headphones of FIG. 1;

FIG. 4 is a left side view of an embodiment of the headphones of FIG. 1;

FIG. 5 is a right side view of an embodiment of the headphones of FIG. 1;

FIG. 6 is a top view of an embodiment of the headphones of FIG. 1; and,

FIG. 7 is a bottom view of an embodiment of the headphones of FIG. 1.

The broken lines in the drawings show unclaimed subject matter only and form no part of the claimed design

1 Claim, 5 Drawing Sheets(56)
